MAXIMILIAN CHARLES SCHWEINERT, OF WEST HOBOKEN, NEW JERSEY, AND HENRY P. KRAFT, OF NEW YORK, N. Y.

PILLOW-VALVE.

1,158,420.

Specification of Letters Patent. Patented Oct. 26, 1915.

Application filed July 11, 1908, Serial No. 443,037. Renewed March 20, 1915. Serial No. 15,903.

To all whom it may concern:

Be it known that we, MAXIMILIAN CHARLES SCHWEINERT, residing in West Hoboken, in the county of Hudson and State of New Jersey, and HENRY P. KRAFT, residing in the borough of Brooklyn, in the county of Kings, city and State of New York, citizens of the United States, have invented certain new and useful Improvements in Pillow-Valves, of which the following is a specification.

This invention relates to valves for air pillows or the like and aims to provide certain improvements therein. In the best forms of such valves heretofore used there has been provided a valve tube which is designed to be connected to the pillow or other article to be inflated, and an elongated cap screwing upon such valve tube and a valve proper swiveled thereto which is adapted to be pressed down over the end of said tube when the cap is screwed home. In this type of valve it is important that the parts be connected together so that they cannot be lost, and that the valve proper shall be swiveled to the cap so that the packing washer which forms a part of the valve proper shall not be distorted when pressed against its seat on the end of the valve tube by the inward rotation of the cap.

Our invention provides a pillow valve or the like in which these desirable features are provided, in which the various parts are very economically constructed and in which such parts are much more durable than those in common use.

Our invention also provides a novel method of swiveling the valve proper to the cap so that such valve proper may be moved at will, and the packing inspected or replaced.

Referring to the accompanying drawings illustrating our invention, Figure 1 is a vertical axial section of our improved valve, the parts being very much enlarged. Fig. 2 is an elevation of the various parts constituting our improved cap. Fig. 3 is a plan of the valve proper.

Referring to the drawings let A indicate a pneumatic pillow or any other device which it is desired to inflate, B the valve tube of

our invention having its lower end vulcanized within the neck C of the pillow A, and D the cap which carries the valve proper E.

55

The valve E is provided with a packing *a* which is designed to be pressed against the seat *b* formed at the outer end of the tube B when the valve is closed. The cap D is preferably screwed upon the end of the valve 60 tube B as shown, in order that the valve may be opened and closed by rotation of the cap. According to the present invention the tube B is screw-threaded near its outer end as shown at *c*, and near its inner end it is provided with a groove *d*. The cap D is provided with a central bore and is internally screw-threaded substantially throughout the length of such bore as shown at *e*. Near the lower end of the cap is arranged a short 65 screw *f*, the inner end of which *g* projects within the groove *d* of the valve tube, and thus limits the outward movement of the cap. The groove *d* is sufficiently wide (in the direction of the length of the tube B) to 70 permit the cap D to be screwed and unscrewed the required extent to open and close the valve, while at the same time, in connection with the screw *f* it prevents the complete separation of the cap from the valve 75 tube, thus avoiding any danger of loss of the cap. This construction provides a valuable improvement over those heretofore in common use. It has hitherto been common to form the groove *d* at the outer end of the 80 tube and to form the screw-thread *e* inwardly thereof. It has been found that the cap would very often screw completely off the thread before its movement was stopped by the screw *f*. When manufactured in 85 large quantities a very considerable percentage of the valves have been found to be defective in this particular. By locating the groove *d* inwardly of the screw-thread *e* this disadvantage is entirely obviated, since it is 90 impossible for the cap to screw off the thread *e*.

Our invention also includes important improvements in the valve proper E. According to our invention such valve proper is 100 formed as a separate member from the valve cap so that it may be easily removed and

replaced. Such valve proper is shown in section in Fig. 1 and in elevation in Fig. 2. Preferably the valve proper is formed of a solid piece of metal *h* recessed at its under side at *j* to receive the packing washer *a*, the latter being held in place by a stud *k*, a shank of which is extended up through the lower part of the member *a*, and its end riveted as shown. The member *h* is provided with a slot *l* into which the end of the stud *k* extends, which slot also forms a passage for the air. To facilitate the operation of rivetting the end of the stud *k*, the slot *l* is enlarged at *n* (Fig. 3) to admit a riveting tool. The valve member *h* is provided on its upper side with a shoulder *o* which is designed to bear against a corresponding shoulder *p* formed at the upper end of the bore of the cap, and said member *h* is also formed with a tubular extension *q* which is designed to fit closely in a circular face *r* formed at the upper part of the cap. By this means the valve proper is held against any tilting movement within the cap so that the packing *a* is brought firmly against its seat as the cap *D* is screwed home.

The valve cap is provided at its upper end with a passage *s* which is preferably screw-threaded as shown so as to permit the cap to be coupled with a pump or the like.

Various means may be employed for detachably swiveling the valve proper to the cap, but we have shown in the drawings the construction which we prefer to employ. In this construction the valve body *h* is formed with a circular groove *t* at its middle, which groove is designed to receive the end *u* of a screw *v* which is threaded into the wall of the cap as shown. The screw *v* is of such dimensions that when it is screwed home it does not bind the valve proper but permits it to rotate relatively to the cap so that it is in effect swiveled thereto.

During inflation the air flows through the passage *s*, thence through the slot *l* in the valve body *h* and laterally out of such slot into the space between the valve body and the cap *D* and thence around the under side of the valve proper into the valve tube *B*.

Our invention presents several advantages over valves now in use. The provision of a valve proper which is detachably swiveled to the cap permits such valve proper to be easily inspected or repaired, and the packing *a* to be replaced. The cap is entirely prevented from working off the tube or from having its screw-thread disengaged from that of the tube. The interior bore of the cap may be screw-threaded from end to end without counterboring any part thereof. This in itself provides a considerable economy in manufacture. Moreover, the percentage of defective valves produced is very much reduced.

We make no claim herein broadly to a

valve proper of the type shown herein having means for preventing lateral expansion of the washer, since this is described and claimed in our application, Serial No. 244,061, filed February 3, 1905.

While we have shown and described one form of our invention we do not wish to be limited thereto since various changes may be made therein without departing from the invention. It will also be understood that while we have shown our invention as applied to a pillow valve, it may be used in other types of valves.

What we claim is:—

1. In a pillow valve or the like, a valve proper, having a recess at its inner end, a slot leading from its top to a point near said recess, a packing in said recess, and a stud for holding said packing therein, said stud having its head below said packing and being riveted at the bottom of said slot.

2. In a pillow valve or the like, a valve cap, and a valve proper therein, said valve proper having a shoulder and a tubular extension above such shoulder, and said cap having a part engaging said shoulder and a face engaging said tubular extension.

3. In a pillow valve or the like, the combination of a valve tube and a cap, one screwing over the other, the inner of said parts having a groove, and a screw-threaded portion, and the outer of said parts having a screw-threaded bore engaging said screw-threaded portion, and means near one end of said bore for engaging said groove, said means engaging said groove between such end of said outer portion and the points of engagement of said screw-threaded portion and bore.

4. In a pillow valve or the like, a valve tube, and a valve cap, said tube having a screw-threaded end, and inwardly of said end a groove, and said cap having a screw-threaded bore, and having means for engaging said groove to prevent complete separation of said tube and cap.

5. In a pillow valve or the like, a valve tube, and a valve cap, said tube having a screw-threaded end, and inwardly of said end a groove, and said cap having a screw-threaded bore, and having a screw for engaging said groove to prevent complete separation of said tube and cap.

6. In a pillow valve or the like, the combination of a valve tube and cap, said tube having a screw-threaded end and said cap having a screw-threaded bore, and said tube and cap having inwardly of such end means for normally preventing removal of said cap from said tube, said means being adapted to permit limited rotary and longitudinal movements of said cap relatively to said tube, and a valve proper opened and closed by such longitudinal movements.

7. In a pillow valve or the like, a cap hav-

ing a bore therein, a valve proper within said bore, said valve proper having a packing washer on its lower face and means for preventing lateral expansion of said packing washer into contact with the bore of said cap, and a swivel connection between said cap and valve proper, said swivel connection having a displaceable part admitting of ready detachment of said valve proper from 10 said cap, whereby said valve proper may be removed from the bore of said cap for the

inspection and replacement of said packing washer.

In witness whereof, we have hereunto signed our names in the presence of two sub- 15 scribing witnesses.

MAXIMILIAN CHARLES SCHWEINERT.
HENRY P. KRAFT.
